UNITED STATES PATENT OFFICE.

JESSE JACKSON, OF KOKOMO, INDIANA, ASSIGNOR TO GLOBE STOVE & RANGE COMPANY, OF KOKOMO, MICHIGAN.

THERMOSTATIC TRIP-SWITCH DEVICE.

1,238,776.

Specification of Letters Patent.

Patented Sept. 4, 1917.

Application filed September 24, 1915. Serial No. 52,496.

To all whom it may concern:

Be it known that I, JESSE JACKSON, a citizen of the United States, residing at Kokomo, county of Howard, State of Indiana, have invented certain new and useful Improvements in Thermostatic Trip-Switch Devices, of which the following is a specification.

This invention relates to improvements in 10 thermostatic trip switch devices for electric stoves and ovens.

The main objects of this invention are:

First, to provide a control device, especially an electric switch, which is tripped 15 automatically by thermostatic action at any readily regulated point.

Second, to provide for the setting of the trip mechanism and adjusting for the desired temperature for tripping by a simple 20 manipulation of a single operating lever or handle.

Further objects, and objects relating to structural details and economies of construction and operation, will definitely appear 25 from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing forming a part of this specification, in which:

35 Figure I is a side elevation of my thermostatic control device with the connections to the supply circuit for the heater shown.

Fig. II is a side elevation of my thermostatic control device with the cover removed 40 showing the switch and trip mechanism.

Fig. III is a detail vertical section through the indicator dial and means for setting the adjusting lever or handle, taken on a line corresponding to section line 3—3 45 of Fig. I.

Fig. III^A is a detail vertical section taken on line 3^A—3^A of Figs. I and III.

Fig. IV is a detail vertical section showing the trip mechanism when set, the same 50 released being shown dotted, taken on a line corresponding to the section line 4—4 of Fig. II.

Fig. V is a detail vertical section through the switch taken on a line corresponding to 55 the section line 5—5 of Fig. II.

Fig. VI is a detail vertical section through the adjustment of the thermostatic rod, taken on a line corresponding to the section line 6—6 of Fig. II.

Fig. VII is a detail horizontal section 60 showing the fastening of the thermostatic rod at one end, taken on a line corresponding to the section line 7—7 of Fig. I.

Fig. VIII is a detail vertical section showing the fastening of the thermostatic rod at 65 one end, taken on a line corresponding to the section line 8—8 of Fig. VII.

In the drawing similar reference characters refer to similar parts throughout the several views, and the sectional views are 70 taken looking in the direction of the little arrows at the ends of the section lines.

In referring to the drawings, I consider the reference characters as representing the parts themselves. 1 is a case which holds 75 the trip mechanism and switch from which depend two supporting bars 2 securely engaging at their lower ends the block 3, the ends of the bars being hooked under the same. Between these two supports is a ther- 80 mostatic rod 4, one end of which passes through block 3 and is pinned thereto. Rod 4 is further guided by loosely passing through guide block 4' which is securely fastened between bars. The other end of 85 rod 4 is secured to an adjusting rod 5 which passes through the case 1. In one end of rod 5 is an adjusting screw 6, together with a lock nut 7. Adjusting screw 6 bears against a latch 7 which is pivoted on a stud 90 8 securely bolted to the case. Latch 7 is made to bear against adjusting screw 6 by the spring 8'. Latch 7 coacts with the catch 9 having a slot 10 at one end. The catch 9 turns about a pin which passes through the 95 slot, said pin being held in a partition 11. The pivoted member 12 of a switch turns about the pin 13 securely held in partition 11 and suitably insulated therefrom, said pin being connected to the heat supply cir- 100

cuit by wire 13'. Switch member 12 supports insulated fiber piece 14 to which is pivoted the adjusting arm 15, said arm passing through and projecting beyond the case 1. The catch 9 is also pivoted to adjusting 105 arm 15. A switch plate 16 is securely mounted to the case 1 and insulated therefrom by a fiber piece 17. On this plate 16 is mounted the auxiliary switch spring 18, said spring being disposed through a slot 110

19' in switch member 19. Into switch member 19 slides the pivoted switch member 12, first making contact when member 12 bears against the knob of spring 18. Plate 16 5 connects with the supply circuit by wire 21. When the switch is opened the knob 20 on spring 18 follows in contact with switch member 12 until it separates from switch member 19 and is the last point of contact.

10 The case 1 is closed by the cover 22 to which is securely held a scale 23. Through the slot 24 of scale 23 passes adjusting arm 15. On the end of arm 15 is secured a knob or handle 25. Over the rod 15 and disposed 15 inside the handle 25 is the spring 26. A sleeve 27 slides on the rod 15 and carries a pointer 27' which is urged against the scale by the spring 26. A portion of the lower end of the sleeve 27 projects into the slot 24 of the scale 23, thereby preventing the sleeve 27 from rotating about the rod 15 and holding the pointer 27' in proper relation to the scale. The curve of the scale is approximately the curve generated by a 20 given point on the rod 15 when the rod 15 is oscillated from left to right. It should be noted that when the rod 15 is swung either to the right or the left the pivot point between the catch 9 and the rod 15 moves in a 25 straight line and the pivot point between the switch plate 12 and the rod 15 moves in an arc about the pivot point 13, thereby causing the curve to flatten out somewhat, as shown at the right hand end of the scale 30 in Fig. IV. It will be clear, however, that a scale may be curved along different curves and the calibration of the scale changed accordingly.

When the device is set, the catch 9 bears 40 against latch 7, (see Fig. IV) and as the temperature rises rod 4 expands thus raising latch 7. When the top of the rod reaches a given height, due to expansion of the rod, the catch 9 is released and the switch is 45 opened by the action of spring 26 bearing against the handle 25. Should a higher temperature of tripping be desired, arm 15 is raised on the scale 23 and the handle 25 is depressed which closes the switch, the latch 50 engaging the catch, thus locking the whole combination. To vary the range of temperature at which my device operates, latch 7 is also raised or lowered from contact with catch 9 by adjusting nut 6, said nut screwing in rod 5 and securely locked by lock nut 7.

Between the mains 28 and the controlling 55 device is the heating coil 29, which may be in an oven or the like, which is opened or closed by the switch 30.

Having thus described my invention, what

I claim as new and desire to secure by Letters Patent is:

1. In an automatic thermostatic switch trip device, the combination with the thermostat rod, a pivoted latch lever to coöperate with said thermostat rod, a catch with a pivot disposed within a slot for adjustment to coöperate with said latch, a contact switch for closing the electric heating circuit, a setting lever pivoted thereto and pivotally connected to said adjustable catch for regulating the position thereof to set the same to be released at a predetermined point, an actuating spring on said adjusting lever for putting tension on the said switch whereby it would be actuated when released, a suitable scale for accurately positioning the said setting lever, all coacting substantially as described for the purpose specified. 65

2. In an automatic thermostatic switch trip device, the combination with the thermostat rod, an adjustable contact end therefore, a pivoted latch lever to coöperate with said thermostat rod, a catch with a pivot disposed within a slot for adjustment to coöperate with said latch, a contact switch for closing the electric heating circuit, a setting lever pivoted thereto and pivotally connected to said adjustable catch for regulating the 80 position thereof to set the same to be released at a predetermined point, an actuating spring on said adjusting lever for putting tension on the said switch whereby it would be actuated when released, a suitable scale for accurately positioning the said setting lever, all coacting substantially as described for the purpose specified. 85

3. In an automatic thermostatic switch trip device, the combination with the thermostat rod, a pivoted latch lever to coöperate with said thermostat rod, a catch with a pivot disposed within a slot for adjustment to coöperate with said latch, a contact switch for closing the electric heating circuit, a setting lever pivoted thereto and pivotally connected to said adjustable catch for regulating the position thereof to set the same to be released at a predetermined point, an actuating spring on said adjusting lever for putting tension on the said switch whereby it would be actuated when released, a suitable 90 scale for accurately positioning the said setting lever, all coacting substantially as described for the purpose specified. 95

In witness whereof, I have hereunto set 100 my hand and seal in the presence of two witnesses.

JESSE JACKSON. [L.S.]
